US00D799599S

(12) United States Design Patent (10) Patent No.: US D799,599 S
(45) Date of Patent: * Oct. 10, 2017

(54) CONTROLLER

(71) Applicant: Microsoft Corporation, Redmond, WA (US)

(72) Inventors: Christopher Kujawski, Seattle, WA (US); Bryan A. Sparks, Sammamish, WA (US); Travis Hosler, Seattle, WA (US); Nicolas Denhez, Seattle, WA (US); Carl J. Ledbetter, Mercer Island, WA (US)

(73) Assignee: Microsoft Corporation, Redmond, WA (US)

() Term: 15 Years

(21) Appl. No.: 29/564,532

(22) Filed: May 13, 2016

(51) LOC (10) Cl. 21-01

(52) U.S. Cl.

USPC D21/333; D14/301

(58) Field of Classification Search

USPC ..... D14/496, 401, 435, 474, 483, 217, 137, D14/138, 160, 168, 356, 203.1–203.8, D14/507; 345/156, 169, 173–179, 905; 715/727–729, 864, 700, 706, 719; 710/1, 710/5, 8; 713/1, 600; 455/1.1, 1.7, 73, 455/344–347, 93, 95, 3.01–3.06, 550.1, 455/573.1; 370/342–344; 369/1, 2, 369/6–12; 463/51–57, 40–47, 1, 29–35; D21/324, 328, 333; 273/148 B

CPC .. A63F 13/00; A63F 13/02; A63F 9/00; G06F 17/00; G06F 19/00

(57) CLAIM

The ornamental design for a controller, as shown and described.

DESCRIPTION

FIG. 1 is a top perspective view of a controller showing our new design;

FIG. 2 is a top view thereof;

FIG. 3 is a bottom view thereof;

FIG. 4 is a front side view thereof;

FIG. 5 is a rear side view thereof;

FIG. 6 is a left view thereof; and,

FIG. 7 is a right view thereof.

The broken line showing of the various unshaded elements of the controller in FIGS. 1-7 is for environmental purposes only and forms no part of the claimed design.

1 Claim, 7 Drawing Sheets
